RETARDATION DEVICE FOR THE RECOVERY
OF PROJECTILE COMPONENTS

Marvin L. Kempton and Everly J. Workman, Socorro, N. Mex., assignors to the United States of America as represented by the Secretary of the Navy

Application May 7, 1952, Serial No. 286,506

2 Claims. (Cl. 102—63)

This invention relates generally to projectile recovery devices, and more particularly to retardation devices for the recovery of projectile components.

The techniques employed in modern warfare require the testing for ruggedness of relatively sensitive electrical and mechanical devices in projectiles in flight, such as proximity fuzes and the like. The development and production of these devices for modern and future guns are facilitated greatly by the possibility of recovering projectile components after flight without these components having been subjected to significant forces and shocks beyond those caused by the gun, and by normal flight conditions.

One conventional way to recover projectile components, such as fuzes, is by a technique known as "vertical recovery." This technique applies readily to guns which can be fired vertically, and which have relatively stable projectiles. The procedure is to fire the projectile at some small departure or angle from the vertical (5 to 20 mils), and collect it in an impact area at some small and reasonably safe distance from the gun (500 to 1,000 yards). A well-stabilized projectile will, under these conditions, return to the ground base first with a large amount of residual spin. If the surface of the ground is reasonably soft, the impact accelerating force may be considerably less than experienced in the gun.

This procedure or technique has been used successfully on guns, such as the 57 mm, 90 mm, 5"/38, 5"/54, 3"/70 and the 120 mm.

Acceleration gages installed in such projectiles over a period of time have indicated, however, that frequently these impact acceleration values may be sufficiently large to invalidate the testing technique. This happens, for example, when the surface of the ground is relatively hard, when the projectiles strike rocks or other hard objects, and/or when a large yaw angle exists at the time of impact.

In all of the guns mentioned above, it has been necessary to mount the gun on an incline in order to provide elevation angles of 90° or more. Although stable flight conditions on the base-first, downward trajectory of the projectiles exist for the above guns under still air conditions, high winds aloft and sheer wind situations may cause tumbling. It is to be remembered, of course, that the stability may be quite different in this reverse direction of travel due to shifting of center of pressure and other aerodynamic effects.

When larger caliber, and possibly higher velocity guns are developed, it may be possible that tumbling may result in the lower atmosphere due to high velocity of fall acquire in rare air aloft, as well as from other shape factors.

The depth of penetration of the projectile depends upon a great number of factors, such as impact velocity, mass of projectile, ratio of mass to length, amount of "boat-tailing," and hardness of the ground. It has been found at some proving grounds, for example, that the depth of

2

penetration has ranged from one (1) to twelve (12) feet for all projectiles.

This method or procedure as set forth above has been very effective as a proof device, and, in fact, has been of tremendous aid in the development of radio proximity fuzes of various types. However, it is cumbersome, laborious, and in many cases misleading.

It is one of the objects of this invention, therefore, to provide a retardation device for the recovery of projectile components which is simple and reliable in operation.

To provide a device for the recovery of projectile components that is inexpensive and capable of being manufactured by reasonably standard processes, and which can be reused, are also other objects of this invention.

And another object of this invention is to provide a retardation device for projectile component recovery that can be installed in standard, or slightly modified standard projectiles.

To provide a projectile component recovery device which will allow for the operation of the components being tested in the gun and in flight without introducing new causes of failure which might result from such effects as setback, side slap in the gun, vibrations during flight, and in the case of proximity fuzes, changes in the loading of the oscillator, are also other objects of this invention.

While certain features and objects of the invention are generalized above, other objects and many of the attendant advantages will be appreciated and understood most readily from a disclosure of a specific embodiment thereof, as illustrated in the accompanying drawings and described herein, and in which:

Fig. 1 is a longitudinal section, partly in elevation, of a projectile embodying one embodiment of the invention;

Fig. 2 is an exploded view of the projectile shown in Fig. 1;

Fig. 3 is a cross-section on line 3—3 of Fig. 1;

Fig. 4 is an enlargement of the delay mechanism of Fig. 1;

Fig. 5 is a perspective view of a projectile component, showing the retardation elements in extended condition;

Fig. 6 is a longitudinal section, partly in elevation, of a projectile embodying a second embodiment of the invention; and

Fig. 7 is a diagrammatic representation of a projectile component recovery range, with projectiles made in accordance with invention being recovered.

In accordance with the present invention, a projectile, such as a 3"/50 rotating projectile, is modified by cutting off two rings from the front end of the projectile, a cavity is bored in the projectile to form a cylindrical wall, and then the base of the projectile is drilled. A plurality of rods made from $\frac{1}{8}$ -inch diameter steel, each 6 $\frac{3}{8}$ -inches long after forming, are bent and welded into the two rings cut from the 3"/50 projectile. This cylindrical array of rods is assembled into a projectile cavity ahead of a flange on a Duralumin (hereinafter to be referred to as "dural") ejecting cup.

A dural bushing is screwed into the space normally occupied by the auxiliary detonator of a proximity fuze. This bushing includes part of a time delay mechanism having a firing pin. The time delay mechanism is in communication with a slow burning explosive train and slow burning ejecting powders.

Upon operation of the proximity fuze when the projectile is in substantially horizontal flight, such as by a target or by pulsing, the squib contained therein is detonated and it, in turn, sets off the explosive train and the ejecting charge. The explosive gases from the charge push the fuze and the cylinder of rods as a unit out of and ahead of the projectile. Under the influence of centrifugal force created by projectile spin, the rods are bent outwardly and substantially transversely to the longitu-

nal axis of the fuze so that upon fall thereof, the rods serve as a retardation or braking arrangement which allows the fuze to be recovered intact from a projectile component recovery range.

Referring now to the drawings, there is shown in Fig. 1 a 3" / 50 anti-aircraft projectile 10 comprising a body 12 with a fuze 14, such as a radio-proximity fuze, or time fuze, mounted in its forward nose portion 16, a retardation device 18, a time delay mechanism 20, and an ejecting charge 22 located in a chamber in projectile 10 near its base 24. It is to be emphasized that the invention to be described now is not limited in application to 3" / 50 anti-aircraft projectiles, but can be used with other types of anti-aircraft and field artillery projectiles to recover projectile components, such as fuzes and the like.

The standard projectile 10, as shown in Fig. 1, is modified by cutting two rings 26 and 28 from the forward end 16 thereof, boring a cavity 30 to form a cylindrical wall 32, and then drilling a bore 34 in the base 24.

Forty-eight (48) rods 36 made from $\frac{1}{8}$ -inch diameter steel, each $6\frac{3}{8}$ -inches long after forming, are bent as indicated by 38, and are then welded, as indicated by welds 40, into the two rings 26 and 28 cut from projectile 10, as shown in Figs. 1 and 2. This cylindrical array of rods comprises the retardation device 18, which is assembled into the projectile cavity 30 ahead of the flange 41 on the dural ejecting tube 42.

A dural bushing 44 is secured, by screws 46, into the recesses normally occupied by the auxiliary detonator of the fuze 14.

Fuze 14 or other components, together with retardation device 18 can be ejected in several different ways, such as premature action of the fuze 14, action of the fuze 14 on a target, pulsing of the fuze 14, or by means of the auxiliary time-delay mechanism 20 without fuze action. The structural arrangement for accomplishing time-delay operation will now be described.

This auxiliary time-delay mechanism 20 is placed inside of a dural lead-in tube 48 in such a manner that it is firmly held on the axis of rotation of projectile 10. This is accomplished by placing one end 49 of tube 48 in a bore 50 of bushing 44, and the other end 52 in the bore 34 located in the base 24 of projectile 10.

This delay mechanism 20 comprises a brass striking hammer 54 which is located in a bore 56 thereof and which is placed forward of the delay mechanism's striking pin mechanism 58 located in bores 60 and 61 of tube 48 adjacent to bore 56. Striking hammer 54 is held in place by a $\frac{1}{16}$ -inch diameter solid solder shear pin 62, which extends through the walls of tube 48 and through the brass hammer 54. Brass hammer 54 weighs 0.0005 pound and, when actuated, strikes the firing pin mechanism 58 with approximately four (4) to five (5) inch-pounds of kinetic energy.

A steel cup 64, holding an igniting powder charge 66 is placed in end 52 of the tube 48. This cup is separated from bore 61 by means of a disk 68 which has a bore 70 therein through which the firing or striking pin 71 of mechanism 58 passes. Steel cup 64 thus supports the delay mechanism 20 during setback in the gun.

The opposite end 49 of the tube 48 has a cylindrical bore 72 therein for receiving a quantity of rifle powder 74 or the like. Powder 74 is set off by the squib (not shown) of the fuze 14, firing through a bore 76 located in the forward end 78 of bushing 44. It is to be noted that bore 72 is spaced from bore 56 by a wall 79.

As previously pointed out, a main ejecting charge 22 surrounds the dural lead-in tube 48 containing the delay mechanism. Slow burning powders are generally used as the ejecting charge 22 in order to give sustained ejecting force for a longer period without exerting excessive pressures. By this arrangement, maximum acceleration force during ejection can be held to a fraction of the initial setback forces in the gun.

In Fig. 6, there is illustrated a projectile 10 embodying

the retardation device 18, but one in which no fuze action is possible since the cylindrical bore 72 in tube 48 containing the powder 74, as shown in Figs. 1 and 4, has been eliminated, and the brass hammer 54 is no longer in open communication with the blast effects from a squib contained in the fuze 14. In this case, ejection of the projectile components are initiated by the time delay mechanism 20, previously described but which will be reviewed briefly.

This time delay unit is located in a cylindrical dural tube 82 which has relatively thick walls. Tube 82 has transverse bores 84 which are in communication with the main ejecting charge 22. The upper end 86 of tube 82 is closed, and it abuts a solid cylindrical member or plug 88. Member 88 occupies the position normally occupied by the auxiliary detonator of a fuze. This member 88 is maintained in position by a set-screw 90 located in the wall 92 of the fuze.

In the embodiment shown in Figs. 1, 2, 3, 4 and 5, ejection of the fuze 14, together with the retardation device 18, as previously pointed out, can be accomplished either by premature action, action of a proximity fuze on a target, action of a fuze from a pulser, or by means of the auxiliary time-delay action.

The operation of the invention will now be described. A projectile 10 having a proximity fuze 14 and embodying the structure shown in Fig. 1 is fired from a gun 90, as shown in Fig. 7. Gun 90 is elevated to an angle so that projectile 10 will have substantially a horizontal trajectory, as indicated by 92.

If projectile 10 passes within the proper distance of a target, such as 94, proximity fuze 14 will function to set off a squib contained therein. The blast from the squib will pass through bore or entrance 76 and will ignite the powder 74 contained in chamber 72 of tube 48. Upon explosion of this powder, the dural tube 48 is fractured and ejecting charge 22 is ignited. The gases generated upon the burning of the ejecting charge 22 drive the dural cup 42 forward, pushing out the fuze 14 and the cylinder of rods 36 of device 18 as a unit ahead of projectile 10. Centrifugal force bends the rods 36 outwardly something like that shown in Fig. 5. The conservation of angular momentum of fuze 14 imposes a rapid decrease in the rotational speed thereof as the retarding rods are bent outward. Fuze 14, together with retardation device 18, falls to a recovery range 96 along trajectory 97 and can be recovered intact. Projectile 10 continues along its normal trajectory 92.

When it is desired to pulse the fuze 14 after a prescribed period of flight by the projectile 10 along its trajectory, a radio signal is sent to the fuze by means of pulsing equipment 98 located near the recovery range 96. This signal is used to operate the fuze 14. The fuze 14 and retardation device 18 are ejected together as a unit as described previously. They fall to the recovery range along trajectory 99.

When it is desired to eject a projectile component or components without fuze action, the auxiliary time-delay mechanism 20 illustrated in Figs. 1 or 6 is used. Upon firing of the projectile 10 from gun 90, setback or inertia forces cause the brass hammer 54 to shear the shear pin 62 and strike the firing pin 71 of mechanism 58. This firing pin 71 passes through bore 70, and sets off the powder 66 contained therein. Upon ignition of powder 66, the gases generated therefrom cause dural tube 48 to fracture and set off the main ejecting charge 22. This charge, upon burning, ejects the retardation device 18 with the projectile components, and these members fall to the recovery range 96 along trajectory 102.

Obviously many modifications and variations of the present invention are possible in the light of the above teachings. It is therefore to be understood that within the scope of the appended claims the invention may be practiced otherwise than as specifically described.

What is claimed is:

1. The combination with a rotating projectile having a body and a fuze, said body having a cavity formed with a cylindrical inner wall and said fuze having an ejecting tube in the cavity spaced from said cylindrical wall; of a retardation device including a pair of rings between the body and the fuze, an annularly arranged series of rods initially lying within the projectile and extending between the cylindrical wall and the ejecting tube, said rods being disposed in parallel, interengaging relation thereby to form a cylinder and having corresponding outer ends bent to extend between the rings for securement thereby, an ejecting charge in the projectile, and detonating means for the charge, said charge, upon detonation by said means and subsequent to discharge of the projectile from a gun, projecting the fuze

and retardation device ahead of said projectile for exposing the rods, said rods being bent radially by centrifugal force for retarding the descent of the fuze.

2. The combination recited in claim 1, including a delayed action mechanism for the detonating means.
